Attorney.

UNITED STATES PATENT OFFICE.

ROLAND T. WRIGHT, OF ST. LOUIS, MISSOURI, ASSIGNOR TO WRIGHT-BUNCHER MFG. CO., OF ST. LOUIS, MISSOURI, A COMMON-LAW TRUST.

SPARK PLUG.

Application filed August 30, 1923. Serial No. 660,086.

To all whom it may concern:

Be it known that I, ROLAND T. WRIGHT, a citizen of the United States, residing in the city of St. Louis and State of Missouri, have invented certain new and useful Improvements in Spark Plugs, of which the following is a specification.

My invention relates to spark plugs, and, more particularly to that of the removable core type as set out in my co-pending application, Serial Number 578,856 and has for its objects to provide a plug which has distinct and practical improvements to overcome certain practical objections to, and defects in, first, the joint connection between the inner metallic core shell and the outer main shell of the spark plug, and, second to permit the core shell to be rotated after being positioned within the outer shell but before the locking member has been applied.

With the above and other objects in view, the invention consists in the novel features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1, is a view partly in sectional elevation and partly in side elevation embodying the features of my invention.

Fig. 2, is a detail, partly in sectional elevation and partly in side elevation clearly illustrating the non-gasket joint between the outer shell and the core holding shell.

Fig. 3, is a detail of the upper end of the outer shell in sectional elevation clearly showing the annular groove and the inclined lock grooves.

In carrying out the aim of my present invention, I employ an outer metallic shell 1 having the usual screw threaded nipple 2 at its lower end and the wrench engaging portion at its upper end. The shell 1 is provided with bores of two different diameters, designated 3 and 4. These bores have straight parallel inner walls connected or united by means of a long tapered shoulder 5 having the ground surface seat 6.

The inner face of the upper bore 3 is provided a suitable distance below the upper edge of the shell 1 with an internal annular groove 7 which communicates with the lower

ends of a pair of opposed vertically disposed grooves 8, the upper ends of which communicate with the upper face of the shell 1.

The inner face of the upper bore 3 is also provided with a pair of opposed internal inclined lock grooves 9 which are positioned intermediate the upper edge of the shell 1 and the internal groove 7 thereof. The grooves 7 also communicate with the opposed vertical grooves 8.

10 represents an open ended core holding shell having bores of two diameters 11 and 12 and provided with the internal shoulder 13. The upper bore designated 11 is provided with internal screw threads 14.

15 indicates the porcelain or insulator core which is of three diameters 16, 17 and 18 forming the shoulders 19 and 20. The insulator core carries two gaskets 21 and 22, which engage the shoulders 19 and 20, respectively. Gasket 21 engages the shoulder 13 of the core holding shell and the gasket 22 engages the lower inclined face 23 of a screw threaded lock nut 24 which has screw threaded engagement with the internal screw threads 14 of the core shell 10 for locking the insulator in removable fixed relation with the core shell. The core shell is provided with a pair of opposed radially directed ears or lugs 25 which are initially receivable in the vertical grooves 8 of the outer shell when positioning the core shell within upper bore 3 of the outer shell 1 and which are receivable in the internal groove 7 when given a slight turn after being lowered into the shell 1. This permits the core shell and insulator to be turned within the shell 1 before being locked therein and also prevents the core shell from falling out of the outer shell if turned upside down before being locked therein.

The lower end of the core shell 10 is slightly tapered with a concaved side surface 26 and at the juncture of the upper end of this surface with the outer upper surface of the shell 10 there is formed a rounded or curved ground circumferential edge 26' which finds a perfect sealed seat with the surface 6 of the tapered internal ground shoulder 5 thereby preventing compressed gas leakage between the inner and outer shells and obviating the necessity of a copper gasket at this point, as will be clearly understood from Fig. 2 of the drawings.

The leak proof connection or joint just 110

referred to is made possible through the medium of the locking collar member 27 which is provided with the opposed radially directed lugs 28 frictionally receivable in 5 the inclined lock grooves 9 of the shell 1, which causes the lower face of the locking collar 27 to tightly engage the upper face of the core shell and force the rounded or curved ground edge of the core shell to perfectly seat itself upon the ground surface 10 of the shoulder 5 of the outer shell 1.

The locking collar or sleeve member 27 is provided with a pair of opposed radially directed handles 29 for manually manipulating the locking collar 27.

The upper face of the locking collar 27 is provided with a pair of upwardly directed lugs 30 which are receivable in a pair of openings or sockets 31 in the upper 20 face of the core shell when it is desired to tighten or loosen the lock nut 24 with relation to the core shell 10.

32 represents the central electrode which passes through the insulator core or porcelain member 15 and which is provided with 25 the lock nut 33 and the thumb nut 34. 35 represents the ground electrode which is fixed to the lower end of the metallic core holding shell 10, so that when ever the core 30 is removed from the outer shell, both electrodes will be removed with the core shell, hence obviating the necessity of removing the outer shell from the engine head to examine or clean the electrodes.

35 From the foregoing description, it is evident that I provide a spark plug, which is strong and durable, easy to manufacture and one which can be quickly assembled or disassembled and the provision of an air 40 tight joint or seat which is held rigid by tightening up the armed locking sleeve which seals the porcelain holding shell to the outer shell and makes the plug positively leak proof while eliminating a copper gasket due to my improved joint construction.

By providing the curved shoulder edge 26' on the core shell, it is evident that the 50 tapered face 6 of the shoulder 5 need not be so perfectly ground as were the shoulder edge 26' also tapered. By having the edge 26' curved, it will permit the shell to rock and find its perfect seat with the surface 6 of shoulder 5 when pressure is applied to 55 the locking sleeve, as is manifest. The internal annular groove 7 is wider than the lugs 25 of the core shell 10, as shown in Fig. 1, to permit rocking movement of the core holding shell in positioning same within the outer shell and also to accommodate 60 for possible wear on the engaging faces of the joint between the curved edge 26' of the core holding shell 10 and the face 6 of the shoulder 5 of the outer shell 1.

65 The many advantages of the herein de-

scribed invention will readily suggest themselves to those skilled in the art to which it appertains.

I do not wish to be understood as having limited myself to the details of construction shown and described, but desire to have it understood that the invention I have shown in the drawings is merely illustrative, as it is manifest that various minor changes may be made in the exact construction and particular arrangement of parts without departing from the spirit of my invention, hence I reserve the right to make any such changes, or modifications as may fairly fall within the scope of the appended claims when fairly construed.

What I claim is:

1. In a spark plug construction, an outer shell having an internal shoulder provided with a ground surface, said shell having an internal groove and a pair of opposed inclined lock grooves, an inner shell having a ground curved circumferential shoulder for contact with the ground surface of the internal shoulder of the outer shell, an insulator carried by the inner shell, an electrode carried by the insulator, an electrode carried by the inner shell and means for locking the inner shell within the outer shell for forming a tight joint between the inner shell and the outer shell.

2. In a spark plug construction, an outer shell provided with an internal tapered shoulder having a ground surface, a core holding shell having a tapered lower end normally out of contact with the tapered shoulder of the outer shell, a curved circumferential ground shoulder intermediate the upper and lower edges of the core holding shell for engagement with the ground surface of the internal tapered shoulder of the outer shell, a locking sleeve carried by the outer shell having its lower face in contact with the upper face of the core holding shell, opposed radially directed handles for the locking sleeve and a lug and groove connection between the outer shell and core holding shell to permit screw pressure being applied to the nongasket joint between the internal shoulder of the outer shell and the curved circumferential edge of the core holding shell.

3. An outer shell for spark plugs having a screw threaded nipple, an internal tapered shoulder having a ground surface and said shell being provided near its upper edge with an internal annular groove communicating with a pair of opposed internal vertical grooves and said shell having a pair of inclined internal lock grooves communicating at opposite ends with said vertical grooves.

In testimony whereof, I have hereunto signed my name to the specification.

ROLAND T. WRIGHT.
